UNITED STATES PATENT OFFICE.

FRITZ LUERSEN, OF PRICE, UTAH.

CLOTHES-LINE SUPPORT AND ADJUSTER.

1,137,505.

Specification of Letters Patent. Patented Apr. 27, 1915.

Application filed January 14, 1914. Serial No. 812,028.

To all whom it may concern:

Be it known that I, FRITZ LUERSEN, a citizen of the United States, and a resident of Price, in the county of Carbon and State of Utah, have invented a new and Improved 5 Clothes-Line Support and Adjuster, of which the following is a full, clear, and exact description.

An object of my invention is to provide an 10 improved clothesline supported on posts or equivalent elements and having associated therewith novel adjusting means.

The invention will be particularly explained in the specific description following.

Reference is to be had to the accompanying 15 drawings forming a part of this specification, in which similar characters of reference indicate corresponding parts in all the views.

20 Figure 1 is a perspective view of the clothesline and pins embodied in my invention; Fig. 2 is a broken sectional side elevation; Fig. 3 is a fragmentary sectional plan view of the supporting means at one end of the line; Fig. 4 is an enlarged view of the 25 slide to which one end of the line is attached, the view being taken looking directly at the top of the post on which the slide is fitted; and Fig. 5 is a perspective 30 view of the clothespins.

In carrying out the illustrated practical embodiment of my invention, two posts 10, 11, or equivalent supports are provided. Between the posts are approximately parallel 35 clothes lines 12. One end of the line is attached to a box-like carriage or slide 13 arranged on the post 10. Connection between the lines 12 and the slide 13 may be through the medium of a bail 14. The opposite ends 40 of the clothesline pass through eyes 15^a in a cross arm 15 on the post 11, and may run over pulleys provided as at 16 on said cross-arm, the ends 12^a of the members forming the clothesline being made fast, in practice, to a 45 cleat 17 or the like.

To raise and lower the slide 13 a rope 18 is provided, which is bent around a sheave or pulley at the end of the post 12, as at 19, one strand or stretch being carried around 50 a roller 20 to effect a frictional connection between the rope and slide. The ends of the rope may be made fast to the cleat 21 provided on any suitable member at the base of the post 10. The slide 13 is provided with 55 friction rollers 22 for bearing against the back of the post 10 in the raising and lower-

ing of the slide. The downward movement of the slide 13 may be limited by a stop pin 23 on the post 10, and the upward movement of the slide may be similarly limited by a 60 pin 23^a at the upper end of the post.

In connection with the clothesline 12 wire clothespins are provided, designated generally by the numeral 24, one of which is shown in Fig. 5. The clothespins are provided with a body formed of a single piece of wire bent into a loop 25, returned on itself, the members being preferably twisted as at 26, at the lower end of the loop 25. Below the twisted or crossed portion 26, the 65 wires carry downward in the form of shanks 27, which are bent outwardly at the lower end, and comprise lateral arms 28, the ends of which may be turned approximately at a right angle as at 28^a. On the shanks 27, 70 clamps 30 are provided, which are also formed of wire doubled on itself around the shanks 27, and carried outwardly in opposite directions to the shanks, and then downwardly in the form of depending resilient 75 arms 31 that embrace the lateral arms 28 on the body. The shanks 27 are bent toward each other at the lower end to provide shoulders 29 for limiting the downward movement of the clamps 30. The clamps 30 may 80 be caused to engage the clothes A, indicated by dotted lines in Fig. 1.

To assemble the clothespins on the lines 12 adjacent to the post 10, a bar 32 is provided, 90 which is slidably fitted on the lines 12, being formed with holes 33 for the free movement of the said bar on the lines. The bar 32 is interposed in a practically endless haul rope 34, one end of which is connected as at 35, with the bar 32, at one side of the latter, the opposite end of the rope being connected as at 36 with the said bar at the opposite side. The rope runs over the pulley, as at 37, on one post 11, and is given a turn around a drum 38 mounted to turn on the slide 13. The drum is provided with a crank handle 39, whereby the drum may be turned to exert a pull on the rope 34 in either direction, for moving the bar 32 toward or from either post 10 or 11. The clothespins 95 24 adjacent to the bar 32 are connected with the latter as by a cord 24^a, so that the said adjacent pins will be drawn toward the post 11 by the said bar.

In practice, the pins are so clamped to 100 the clothes that the latter will form a connection between adjacent pins and the haul-

ing of those pins adjacent to the bar 32 will result in drawing the pins and clothes in succession toward the post 11. A reverse movement of the bar 32 will obviously cause the said pins to be assembled adjacent to the post 10. By the described arrangement the clothes may be conveniently hung and removed.

Having thus described my invention, I claim as new, and desire to secure by Letters Patent:

1. The combination of a pair of clothes-lines, a slide to which the lines are connected at one end, a post on which said slide is adapted to be raised or lowered, means for raising and lowering the slide, a post to which the opposite ends of the lines are connected, a series of pins on the lines, a cross bar fitted to slide on the lines, a haul rope connected with said bar, and extending in opposite directions therefrom to the posts, the said haul rope having a running con-

nection with one post, and means on the slide of the other post for moving said rope to or from either post.

2. The combination of end supports, a slide movable on one of said supports, a clothesline connected at one end with the slide, and connected at its opposite end with the opposite support, a series of pins strung on the line for sliding movement thereon, a bar slideable on the line, a haul rope connected with said bar and extending in opposite directions toward the supports, the rope having running connection with one of the supports, and a drum on the slide, around which the haul rope is given a turn.

In testimony whereof I have signed my name to this specification in the presence of two subscribing witnesses.

FRITZ LUERSEN.
